UNITED STATES PATENT OFFICE.

LOUIS CLÉMENT GASTON RIVIERRE, OF PARIS, FRANCE.

TRANSMISSION MECHANISM FOR MOTOR-CYCLES.

No. 811,327

Specification of Letters Patent.

Patented Jan. 30, 1906.

Application filed October 31, 1904. Serial No. 230,843.

To all whom it may concern:

Be it known that I, LOUIS CLÉMENT GASTON RIVIERRE, a citizen of the Republic of France, residing in Paris, in the Republic of France, have invented certain new and useful Improvements in Transmission Mechanisms for Motor-Cycles, of which the following is a specification.

This invention relates to transmission mechanisms for motor-cycles and similar machines or vehicles, and has for its object the provision of means whereby the starting of the motor may be readily effected through the medium of the pedals.

A further object of the invention is the provision of such a mechanism in which the motor may be readily started before the starting of the machine, so that it is unnecessary to push the latter by pedaling and so that a handle or belt-gear for starting the motor is rendered unnecessary.

The invention also aims to provide a mechanism in which the transmission-chain or other gearing from the motor may be readily removed, so that it is possible to drive the machine in case of a breakdown of the motor by pedaling either with the ordinary or a change-speed gear.

With these ends in view the invention consists in the novel features and combinations of parts, to be hereinafter described and claimed.

In the accompanying drawings, in which similar reference characters denote the same parts throughout, Figure 1 is a vertical central section through a transmission mechanism constructed in accordance with the invention, and Fig. 2 is a detail elevation of one of the cams for actuating the clutch.

Referring to the drawings, 1 indicates a fixed axle, such as used in ordinary cycles and motor-cycles. A hollow spindle 2 rotates freely about the fixed axle upon the ordinary ball-bearings, as shown, and at one end of the hollow spindle 2 is keyed in any suitable way a sprocket 4, adapted to receive movement from the motor through the medium of a sprocket-chain or other transmission-gear. A sleeve 25 is keyed upon the opposite end of the hollow spindle 2 and is capable of movement longitudinally thereof. This sleeve 25 carries a fixed sprocket 5, adapted to transmit motion by means of a sprocket-chain or other transmission device from the cranks of the machine, said sprocket 5 being fixed, as will be obvious, to the spindle 2 and incapable of independent rotary movement. Adjacent the

sleeve 25 is arranged a disk 37, adapted to bear against the same, and two superposed cams 26 26' are adapted to shift said disk longitudinally through the medium of ball-bearings, which are interposed between the inner cam 26 and said disk, the cams 26 and 26' being provided with grooves or serrations which are adapted to be placed in or out of register, according to the relative angular position of the cams. The cams 26 and 26' are provided with tailpieces 27 and 27', respectively, said tailpieces being perforated, as shown. The tailpiece 27' is fixed in a suitable manner (not shown) with the frame of the machine, while the other tailpiece is adapted to be connected to a suitable rod, whereby the shifting of the cams and the axial movement of the sleeve 25 may be effected.

The hollow spindle 2 carries a bearing-ring 29, of suitable metal, which abuts at one end against ball-bearings 30, interposed between the same and the sprocket 4. The hub proper of the mechanism is adapted to rotate freely about said bearing-ring, and said hub 80 comprises two disks 3, which are clamped together by means of tubular members 31. The members 31 are interiorly and exteriorly threaded and provided with intermediate shoulders, against which one of said disks 85 constituting the hub is clamped, while the other disk is clamped against the same by means of a nut 30^x engaging the exterior threads of the tubular members. At their opposite ends the parts 31 are screwed into a ring 32, which maintains the same rigidly in position. These parts also serve to seat helical springs 23, the tension of which may be regulated by means of nuts *h* engaging the interior threads of said parts and abutting 95 against the ends of said springs. The function of these springs will be more particularly described hereinafter.

One of the disks 3, constituting the hub, is provided with a cone-ring 35, which is clamped 100 to the periphery thereof by means of screws, as shown, and provided upon its conical surface with a layer 36 of fibrous or other material, adapted to augment the friction between the ring 35 and a cone clutch member 22 24. 105 The clutch member 22 24 is freely rotatable about the part 25, rotating upon a bearing-ring 34 thereon. The hollow spindle 2 has keyed to it, intermediately of the sprockets 4 and 5, a pinion 14, which meshes with a plurality of planetary pinions 15, journaled upon stud-pins 16, which pass through two

parts of the hub 3 and are secured thereto by means of nuts 16', said stud-pins being fixed at their opposite ends to the ring 32. The clutch member 22 24 is provided with an internally-toothed crown 17 at the periphery thereof, which meshes with the planetary pinions 15, as shown. A clutch-strap 40, encircling the part 24 of the member 22 24, serves to brake said member.

Upon a shifting of the cam 26 the clutch member 22 24 is shifted against the action of the springs 23 out of engagement with the cone-ring 35—viz., out of its normal position. This is its free or disengaged position. It is apparent that upon the rotation of the hollow spindle 2 the pinion 14 will drive the planetary pinions 15 and impart to them an epicycloidal movement which will cause the rotation of the member 22 24 through the medium of the internally-toothed crown 17. In order to effect the rotation of the hub at a reduced speed, the member 22 24 is braked by means of the clutch-strap 40, so that said clutch member, being thus rendered stationary, will cause the rotation of the planetary pinions 15, and thereby transmit motion to the hub 3, which will be rotated at a reduced speed, as will be obvious. Upon the shifting of the cam 26 in the opposite direction the member 22 24 and the hub will be locked, and the hub 3 will then be rotated at the same speed as the sprockets 4 and 5.

By my invention a mechanism is provided by which the use of a hand-crank or other similar device for starting the motor before mounting the motor-cycle is obviated. It is possible by the improved mechanism to readily remove the transmission-chain from the motor and to propel the machine by means of the pedals independently of the motor, it being possible to use either of two speeds.

Having thus described my invention, I claim as new and desire to secure by Letters Patent—

1. In a two-speed transmission mechanism, in combination, a fixed axle, a hollow spindle rotatable thereon, sprockets carried by said spindle, a hub rotatable on said spindle, a pinion carried by said spindle, planetary pinions on said hub engaging said pinion, a member rotatable on said spindle and adapted to be frictionally locked to said hub, a gear on

said member meshing with said planetary pinions, and means for braking said friction member.

2. In a transmission mechanism for motor-cycles, in combination, a fixed axle, a hollow spindle rotatable thereon, sprockets carried by said spindle, a hub rotatable on said spindle, a cone-ring attached to said hub, planetary pinions carried by said hub, a pinion on said spindle meshing with said planetary pinions, a cone member rotatable on said spindle and having an internally-toothed crown meshing with said pinions, means for shifting said cone member into and out of engagement with said cone-ring, and means for braking said cone member.

3. In a transmission mechanism for motor-cycles, in combination, a fixed axle, a tubular spindle rotatable thereon, sprockets carried by said spindle, a hub rotatable on said spindle and carrying a cone-ring, a pinion fixed to said spindle, planetary pinions on said hub engaging said pinion, a cone member rotatable on said spindle and axially shiftable therewith, a toothed ring carried by said cone member and engaging said pinions, springs carried by said hub for normally maintaining said cone member in engagement with said cone-ring, means for shifting said cone member against the action of said springs, and means for braking said cone member.

4. In a transmission mechanism for motor-cycles, in combination, a fixed axle, a hollow spindle rotatable thereon, sprockets carried by said spindle, a hub rotatable on said spindle, a cone-ring carried by said hub, planetary pinions journaled at one side of said hub, a pinion on said hub meshing with said first-named pinions, an internally-toothed cone member rotatable on said spindle and meshing with said pinions, means for braking said cone member, means for normally maintaining said cone member in engagement with said cone-ring, and means for axially shifting said cone member in either direction.

In testimony whereof I have signed this specification in the presence of two subscribing witnesses.
